UNITED STATES PATENT OFFICE

2,152,572

SADDLE FOR CYCLES

Earl W. Swett, Alma, Mich., assignor to The Lob-
dell-Emery Manufacturing Company, Alma,
Mich., a corporation of Michigan

Application April 24, 1936, Serial No. 76,271
Renewed March 8, 1938

7 Claims. (Cl. 155—5.20)

This invention relates to saddles for cycles such for instance as are commonly used in connection with bicycles and motorcycles for resiliently supporting the weight of the rider thereof.

Saddles of this type are commonly provided with cushioning means, generally including metallic springs and it is the object of the present invention to provide a new and improved cushioning means which is particularly applicable for use in connection with a saddle embodying a seating member and a reach member adapted for relative bodily movement. The reach member of the saddle comprises an elongated member disposed beneath the seating member and extending longitudinally thereof, this reach member being adapted to be in turn connected to and supported by the customary saddle post.

In the preferred form of the invention the reach member is hingedly connected to the seating member at one end and its other end, hereinafter designated the free end, is connected to the seating member by a novel mechanism including a device in the nature of a toggle, a tension spring being associated with this device and yieldingly opposing relative movements of the parts of the toggle and hence relative movements of the reach member and seating member toward each other.

One embodiment of the invention will be disclosed by way of example but one skilled in the art will appreciate that minor changes in design and arrangement of the component elements thereof may be made, in adapting the invention to saddles of different types, without departure from the teachings of the invention.

In the drawing:

Figure 1 is a side elevation of the saddle showing the improved cushioning means;

Figure 2 is a bottom plan view of the same;

Figure 3 is a section on line 3—3 of Figure 2;

and

Figure 4 is a section on line 4—4 of Figure 3, the operative parts of the mechanism, however, being shown in different positions by the use of full dotted lines.

The seating member is indicated at 10 and the reach member at 11. While the specific constructions of these two members may vary widely, I prefer to form the seating member by shaping a metal sheet into the desired form by a pressing operation and prefer to form the reach member 11 of two parallel flat bars, indicated at 12 and 13 in Figure 2. The forward ends of these bars are provided with aligned apertures, respectively, and through these apertures, and through the aligned apertures of the lugs 14 and 15 projecting downwardly from plate 16 secured to member 10 are passed a pivot member or bolt 16, the reach member being thereby pivotally or hingedly connected to the forward end of the seating member.

The free end of the reach member, i. e., the

end remote from pivot 16, is connected to the seating member through a toggle-like device which includes the link 17 and the arms 18 of bell crank levers L and L'. Link 17 comprises a flat base portion 17' and flanges 17² and 17³, a bolt or rivet 19 passing through aligned apertures in the flanges and also through aligned apertures in the reach member parts 12 and 13 so that the link is hingedly connected to the end of the reach member. A spacing sleeve encircling bolt 19 is indicated at 20.

The two bell crank levers L and L' are preferably identical and one only need be described. The arm 18 of bell crank L has its lower end inwardly turned to pass through an aperture formed in the upper end of link 17³. At its upper end the arm 18 has two aligned horizontally extending portions 22 and 23, portion 23 extending through an aperture formed in flange 24 of bracket member 25 rigidly secured to the seating member and the aligned portion 22 resting in a notch formed in a similar flange 26 also depending from the bracket plate 25. Intermediate the aligned portions 22 and 23 of the bell crank L is the U-shaped second arm of this lever, indicated at 27. From an inspection of Figures 1 and 4 it will be perceived that the arms 18 and 27 are disposed at an acute angle to each other. To the curved mid portion of the arm 27 is connected one end of the coiled tension spring 30. The opposite end of spring 30 is closely coiled about a grooved core 31 which is rigidly secured by means of a bolt 32 to the depending bracket arm 33 integral with plate 25, this plate being secured firmly to the seating member 10, as by means of bolts, one of which is indicated at 34, or by welding or otherwise.

When the saddle is unloaded its parts occupy the relative positions in which they are shown in Figure 1 and in full lines in Figure 4, the spring being retracted and compacted and the base plate 17' of the link member 17 having its forward or inner face contacting with the end surfaces of the reach member parts 12 and 13, the end of the reach member thereby comprising a limited stop 45 for counterclockwise rotation of the link 17 about its pivotal supporting bolt or rivet 19. When weight is superposed upon the seating member it will be depressed, the reach member being rigidly suspended by the seat post in the customary way, 50 the seating post being, however, not illustrated. Any suitable type of seat post is adapted for use in combination with the improved saddle. As the seating member is depressed, for instance when it moves from the position in which it is shown 55 in dotted lines, the toggle device comprising link 17 and crank arm 18 will be actuated, the thrust of link 17 upon the arm 18 causing the bell crank L to rotate in a counterclockwise direction against the action of spring 30. Spring 30 will be ex- 60

tended and will elongate to some such position as indicated in dotted lines in Figure 4. The extent of elongation of the spring will be dependent upon the load imposed upon the seating member, as is well understood. The two springs shown, therefore, will carry the weight of the rider, acting through the bell cranks and links illustrated and the springs, thus distended, are still free to expand further and contract as will be necessary as the vehicle upon which the saddle is mounted passes over inequalities in the roadway, the bell cranks L and L' rocked about their common pivotal axis in either direction of rotation, depending upon whether the springs 30 are expanding or contracting. The relative lengths of arms 18 and 27 of the levers may be varied in different saddles, and likewise springs of different capacity may be used, all with the end in view of promoting maximum riding comfort for 20 riders of different weights.

Having thus described the invention, what is claimed as new and desired to be secured by Letters Patent is:

1. In a saddle for cycles, in combination, a seating member, a reach member extending longitudinally of the seating member and having one end hingedly connected thereto, and means for yieldingly opposing movement of the seating member toward the reach member, said means including a tension spring extending longitudinally of the seating and reach members and disposed upon one side of the longitudinal center line of said members and parallel thereto, means supporting said spring at one end upon one of said members and means connecting the other end of said spring to the other of said members, said last named means comprising a rock shaft having a transverse horizontal portion rotatably mounted upon the member from which said spring 40 is supported, and a pair of crank arms on said rock shaft which are spaced apart in a direction transverse to said seating and reach members, one of said crank arms connected to the free end of said spring and the other operatively connected 45 with said other member.

2. In a saddle for cycles, in combination, a seating member, a reach member extending longitudinally of the seating member and having one end hingedly connected thereto, and means for yieldingly opposing movement of the seating member toward the reach member, said means including a tension spring extending longitudinally of the seating member, means connecting one end of the tension spring to the seating member and means including a crank and link for operatively connecting the free end of the reach member to the other end of the spring.

3. In a saddle for cycles, the combination with seating and reach members of means for yieldingly resisting relative movement of said members toward each other, said means including a two-armed lever pivotally mounted on the seating member, a link connecting one arm of said lever to the free end of the reach member, and resilient means opposing movement of said lever under the thrust of said link, said reach member and link being provided with mutually engaging parts which limit the rocking movement of the lever under the influence of the spring.

4. In a saddle for cycles comprising a substantially rigid seating member or base, a reach member extending longitudinally of said seating mem-

ber, one end of said reach member being connected to one end of said seating member in such manner that said seating member may swing bodily about said connection toward and away from said reach member, the combination of means for yieldingly resisting relative movement of said members toward each other, said means including a two-armed lever pivotally mounted on the seating member, a link connecting one arm of said lever to the free end of the reach member and adapted to move said lever when said seating and reach members are moved relatively to each other, and a tension spring connecting one of said members with a portion of said lever and adapted to be extended in opposing movement of said lever under the thrust of said link.

5. In a saddle for cycles, the combination with seating and reach members of means for yieldingly resisting relative movement of said members toward each other, said means including a two-armed lever pivotally mounted on said seating member, said reach member having a squared free end, an element pivotally connected to one side of said free end of the reach member and adapted to abut said end upon limited pivotal movement of said element upon the occurrence of relative separating movement between said members, one arm of said lever being pivotally connected with said element, and a spring connecting the other arm of said lever with one of said members for resiliently opposing pivotal movement of said lever and element.

6. In a saddle for cycles, the combination with seating and reach members of means for yieldingly resisting relative movement of said members toward each other, said means including a centrally disposed element pivotally mounted upon the free end of said reach member, a pair of two-armed levers each being pivotally mounted upon said seating member on either side thereof, one arm of each of said levers being connected with said element, a pair of tension springs disposed one upon either side of said seating member and respectively connected with the other arms of said two-armed levers to resiliently resist pivotal movement of said levers and said element, said element and the end of said reach member adapted to abut upon limited relative movement in one direction in order to limit the swinging movement of said seating and reach members in directions away from each other.

7. In a saddle for cycles, the combination with seating and reach members of means for yieldingly resisting relative movement of said members toward each other, said means including a centrally disposed element pivotally mounted upon the free end of said reach member, a pair of levers each being pivotally mounted upon said seating member on either side thereof, a portion of each of said levers being connected with said element, a pair of springs disposed one upon either side of said seating member and respectively connected with other portions of said levers to resiliently resist pivotal movement of said levers and said element, said element and the end of said reach member adapted to abut upon limited relative movement in one direction in order to limit the swinging movement of said seating and reach members in directions away from each other.
